MATTRESS SIDE AND METHOD OF MAKING THE SAME

Filed June 20, 1932

UNITED STATES PATENT OFFICE

2,048,951

MATTRESS SIDE AND METHOD OF
MAKING THE SAME

Harry Rosenberg, St. Paul, Minn.

Application June 26, 1932, Serial No. 618,274

3 Claims. (Cl. 5—360)

My invention relates to an improvement in mattress side and the method of making the same, providing a means of placing flat staple-like members through the material forming the outside and inside sheathing of the side of a mattress or the like, the flat staples forming a broad engagement on the outside surface of the side of the mattress, and the inner ends thereof being clinched over at spaced apart points to provide a strong anchoring means forming tufts in the sides of the mattress.

A feature resides in the method consisting in placing a series of flat or round wire staple-like members with a broad engaging surface, spaced in rows in line with each other to provide a tufting means of a different character than has been used heretofore.

It is also a feature to provide a decorative means by the anchoring staples which tuft the sides of the mattress and which tend to hold the padding between the inner and outer side walls of the side of the mattress in position so as to prevent slipping of the inner padding material, and at the same time providing a decorative means by staples of a character having a broad flat surface which show in a series of rows along the sides of the mattress. When these staples are anchored in the side, they not only form a strong and more durable means of anchoring the sides together and holding the tufting in place in the side wall of the mattress, but are very attractive and may be placed in different relations to each other so as to decorate the side wall of the mattress, giving it a pleasing appearance.

Heretofore, different means have been used for tufting the side walls of a mattress, including stitching by sewing through the sides, and padding, eyeletting, and other means, however, with my means of providing a flat staple which is set into the side walls to anchor the ends on the inside of the side wall, with the ends spaced apart and bearing toward the flat outer surface of the staple, a more efficient and practical means for tufting the sides together is provided. Further, these anchoring staples do not detract from the side appearance of the mattress but rather give a pleasing appearance and more particularly when they are placed in even rows or in line with each other, extending across transversely of the side walls.

Further, the method consists in placing a series of staple members in longitudinal alignment in rows transversely to the side wall of the mattress.

The details and features of the construction of

my side wall of a mattress will be clearly and fully set forth, together with other objects.

In the drawing forming part of this specification:

Figure 1 is a side elevation of the side wall of a mattress wherein my improvement and method is employed.

Figure 2 is a section on the line 2—2 of Figure 1.

Figure 3 is a section on the line 3—3 of Figure 2.

Figure 4 is a side elevation showing my improvement and method carried out in a different manner than that illustrated in Figure 1, showing a portion of a side wall of a mattress or the like.

Figure 5 is a side elevation of a portion of the side wall of the mattress and the like, showing another means of carrying out my invention and method of reinforcing a padded side wall.

Figure 6 illustrates a perspective of the tufting staple used in carrying out my improvement and method.

The drawing illustrates the side wall A of a mattress or similar article where a padded wall or side of an article is desired to be formed so as to reinforce the same and to provide a means of tufting the padding between textile side walls so as to hold the padding in a tufted sheet-like formation. The side wall A may be attached by stitching 10 to the roll 11 of the top 12 and bottom 13 of a mattress B to support the wall A in a manner to extend between the top and bottom 12 and 13 and to form a reinforced side wall extending around the mattress.

The side wall A is formed with an outer textile sheathing 14 and an inner textile sheathing 15 between which a sheet-like layer of cotton padding 16 is placed. In carrying out my method I provide a means of tufting the wall A by automatically placing a series of wire staple members 17 which are made of flat or round wire in longitudinal alignment in a series of rows spaced apart, the longitudinal extension of the staples being preferably transverse through the wall A so that the transverse line extends from the top 12 to the bottom 13, as illustrated in Figures 1 and 2. The flat staple members 17 may be formed in any suitable manner and are provided with a wide body portion 18 of a flat ribbon-like nature from which the shanks 19 extend and when the staples 17 are clinched to tuft the sides 14 and 15 together, the ends 20 are clinched over but spaced apart, thereby providing a wide gripping tufting means extending

through the sides 14 and 15 and adapted to form a means of tufting the padding 16 between the side walls 14 and 15 so as to tend to form a reinforcing means extending transversely across the side wall A. The staples 17 are spaced apart in any suitable manner.

The ribbon-like body 18 of the staple 17 provides a flat bar-like engagement on the outer surface 14 of the side wall A which forms a desirable reinforcing tufting means in the wall owing to the broad engagement of this bar-like portion against the outer textile wall 14. This permits the staples 17 to provide a better means of tufting the wall A and also provides a means wherein the gripping ends 20 are spaced apart so that they will not easily pull out of or through the wall 15 after they have been clinched. The staples 17 also provide a decorative means for the side wall A of a very desirable nature.

20 In Figure 4 I have illustrated the staples 17 positioned in the side wall A extending longitudinally in the wall rather than with the longitudinal extension of the body 18 transverse of the wall A, as heretofore set forth. When the staples 17 are placed in this manner the longitudinal alignment of the rows of staples extends longitudinally with the side wall A. Thus the reinforcing in the side wall has a tendency to form a longitudinal line or crease along through the side wall A when the staples are placed this way. In the placing of the staples in Figures 1 and 2, the staples 17 are placed end to end transversely through the side wall A, whereas, in the positioning of the staples 17 in Figure 4, the staples are side to side in transverse rows along the wall A.

In Figure 5 I have shown the combined placing of the staples like in Figure 1 and like the positioning in Figure 4. In this last placing of the staples, one transverse row of staples would be placed side to side, while the next transverse row would be placed end to end. Then the next transverse row of staples 17 would be placed side to side and the next row end to end, thus forming not only a decorative means for the side wall A of a mattress or the like, but a peculiarly desirable reinforcing tufting means with a broad, flat bar-like engagement which is strong and durable and much more desirable than other forms that have been used to tuft the side walls of mattresses and the like heretofore.

50 My method consists in reinforcing a padded side wall by placing a series of rows of broad staple-like members made of flat or round steel wire 55 which form tufting engagements spaced apart in

the padded side wall. In making the side walls for mattresses such as A, the rows of staples 17 are placed automatically, a row at a time, transversely across the side wall and while I have not illustrated the machine for accomplishing this result, I have provided such a machine which places the staples automatically in position to tuft the padding between the sides as the staples are clinched. The staples may be of metal or any other suitable material, having a decorative finish of any suitable character so as to provide an attractive tufting means extending through the padded wall where the textile sheets cover the padding on each side thereof and the tufting staples acting to clinch the padding and walls together at intervals. This means of making a side wall for mattress cushions and the like is very desirable and more durable than other means which have been used heretofore.

20 In accordance with the patent statutes I have set forth the principles of my mattress side and method of making the same and desire to have the invention interpreted within the scope of the following claims and applied to uses in accordance therewith.

25 I claim:

1. Side walls for a mattress and the like including, a sheathing-like padding of cotton or similar material, textile sheet portions adapted to cover the inside and outside of said padding, and 30 a series of flat tufting staple members fastening said sheet portions together and arranged with the shanks thereof extending vertically in longitudinal alignment in a series of rows equally spaced apart to provide vertical bulging columns 35 in said side wall.

2. In a mattress, a boxing composed of inner and outer fabric strips and an interposed filler, vertical rows of metal staples fastening the strips together, the shanks of the staples extending 40 vertically in spaced relation to each other and the shanks of the several rows being horizontally aligned whereby to divide the boxing into series of vertically rigid horizontal zones alternating with vertically flexible zones thereby limiting collapse 45 of the boxing under pressure.

3. In a mattress, a boxing composed of inner and outer fabric strips and an interposed filler, vertical rows of metal staples fastening the strips together, the shanks of the staples extending vertically in spaced relation to each other, whereby 50 to define vertically extending columns limiting collapse of the boxing under pressure.

HARRY ROSENBERG. 55
